Henry Williams

UNITED STATES PATENT OFFICE.

GEORGE H. JENNINGS, OF BROCKTON, MASSACHUSETTS.

SAFETY ATTACHMENT FOR GAS-BURNERS.

No. 922,770.

Specification of Letters Patent.

Patented May 25, 1909.

Application filed October 23, 1908. Serial No. 459,169.

To all whom it may concern:

Be it known that I, GEORGE H. JENNINGS, a citizen of the United States, residing in Brockton, in the county of Plymouth and 5 State of Massachusetts, have invented a new and useful Improvement in Safety Attachments for Gas-Burners, of which the following is a specification.

This invention relates to that class of 10 safety-attachments for gas-burners in which a pilot-light is employed, and it consists in the novel construction and arrangement of parts whereby when the gas is accidentally extinguished or blown out the mechanism 15 connecting the gas supply - pipe and the burner is automatically closed, thus shutting off the supply of gas to the burner.

The nature of the invention is fully described in detail below, and illustrated in the 20 accompanying drawing, in which my attachment is illustrated as applied to a gas-burner of the general type to which the Welsbach burner belongs, such type of burner being that to which this invention is particularly 25 adapted.

In the drawing the invention is shown partly in vertical section and partly in elevation, and a small portion of the burner, chimney and supply-pipe are represented as 30 broken out.

Reference-numeral 1 represents a supply-pipe provided with the usual gas-cock 2.

3 represents a burner constructed substantially as usual, 4 is the chimney support-35 ed thereby, 5 the mantle and 6 the mantle-support or holder.

The connection between the supply-pipe 1 and the burner 3 comprises a pipe 7 screwed on the upper end of the supply-pipe whereby 40 a chamber 8 is produced, a pipe 9 integral with said pipe 7 screwed at its upper end into the burner and provided with a horizontal partition 10 which has a conical valve-seat 11 connecting with the chamber 8, and an 45 upwardly extending pipe 12 integral with the portion 7, thickened at one side and provided in such thickened portion with a passage 13 which is connected by a passage 14 with the chamber 8—all these parts 7 to 12 50 inclusive being one integral piece. The passage 14 is adapted to be opened and closed by means of a pilot-valve or cock 15. The pipe 12 contains the passage 16 which connects with the adjusting pipe 17 which has screwed into 55 its upper end the nipple 18. This nipple 18 has fitted into it the lower end of the copper

expansion-tube 19 which is provided at its lower end with an integral flange 20 which is held between the lower end of the nipple 18 and shoulder 21 in the pipe 17. The copper tube 19 extends up vertically through a suitable opening 22 in the burner 3 and parallel with the mantle 5, its upper end being provided with a cap 23. Secured to the outer end 24 of the mantle-holder 6 and extending 65 through said cap 23 is a valve-stem 25, preferably of steel, which extends down through the entire length of the copper tube 19 and through the passage 16, and has rigid with its lower end a valve 26 which is of a shape 70 which corresponds to that of the valve-seat 11. A tube 27 extends up from the passage 13 through a suitable opening 28 in the burner 3, and its upper portion 29 is parallel with the copper tube 19 and is closed at its 75 extreme upper end 30, and apertures 31 are formed on the side of the portion 29 which is next the copper tube 19.

When the gas is to be lighted the main cock 2 and the pilot-valve 15 are turned on, 80 this being the position of the parts illustrated in the drawing, and the gas passes from the pipe 1 through the chamber 8 and passages 14 and 13 into the tube 27, and is lighted in the usual manner at the apertures 31 at the 85 upper end of said tube. The pilot-light in a few seconds expands the copper tube 19 in the direction of its length, and as its lower end is seated and stationary by means of the flange 20 the expansion is upward and raises 90 the upper end so that the valve-stem 25 is lifted by the cap 23 and the valve 26 is raised off its seat 11 thus allowing the main body of gas to pass from the tube 1 through the chamber 8 into the pipe 9, and thence into 95 the burner where it is ignited by the flames issuing from the apertures 31, affecting the mantle in the usual manner. As soon as this gas is lighted the pilot-valve 15 is shut off, 100 causing all the gas to pass up into the burner. Inasmuch as the copper tube is very long, 105 and the perforations 31 are in line with and near the tube, but a very few seconds are required to expand it sufficiently to lift the valve 26 from its seat. Now should the gas be blown out accidentally or otherwise, the copper-tube immediately begins to cool and contract, and as its lower end is fast the upper end is lowered and the valve-stem 25 moves the valve 26 onto its seat, thus entirely shutting off the flow of gas into the passage in the pipe 9—it being remembered that the pilot- 110

valve 15 was closed as soon as the gas flowing into the burner was ignited. Thus no gas is allowed to escape even though the main cock 2 is open. The parts 17 and 18 are adapted 5 to be suitably adjusted in order that the lower end of the expansion-tube 19 may be at such a point that when the gas is fully turned on the expansion would be just sufficient to seat the valve 26 without buckling 10 or bending the valve-stem 25.

Having thus fully described my invention, what I claim, and desire to secure by Letters Patent, is:—

1. In a safety-attachment for gas-burners 15 of the character described, a pipe adapted to be secured at one end to the gas-supply-pipe and at its opposite end to the burner; a partition extending across said pipe near its lower end and provided with a port which 20 constitutes a valve-seat; an upward tubular extension rigid with the pipe; a copper expansion-tube rigidly connected at its lower end with said extension and extending up through the burner and parallel with the 25 flame or mantle; a valve-stem made of a less expansive metal than the expansion-tube and extending through said tube from its upper end to its lower end and into the tubular extension; a valve secured to the lower 30 end of the valve-stem and adapted to fit said valve-seat, the upper end of the valve-stem being adapted to support the holder of an incandescent mantle; and a pilot-light connected with the pipe which is secured to the 35 supply-pipe and opening into the chamber below the partition in said pipe; the outlet holes in the tube of the pilot-light where the gas is to be ignited being located near the expansion-tube, for the purpose set forth.

40 2. In a safety-attachment for gas-burners of the character described, a pipe adapted to be secured at one end to the gas-supply-pipe and at its opposite end to the burner; a par-

tition extending across said pipe near its lower end and provided with a port which 45 constitutes a valve-seat; an upward tubular extension rigid with the pipe; an adjusting pipe screwed into the upper end of the upward extension; a nipple screwed into the upper end of the adjusting pipe; a copper 50 expansion-tube with its lower end held rigidly between the adjusting pipe and the nipple and extending up through the nipple and the wall of the burner and substantially parallel with the flame or mantle for substantially its 55 entire length; a valve-stem made of a less expansive metal than the expansion-tube and extending through said tube from its upper end to its lower end and into the tubular extension; a valve secured to the lower 60 end of the valve-stem and adapted to fit said valve-seat, the upper end of the valve-stem being adapted to support the holder of an incandescent mantle; a pilot-light construction formed in one wall of the pipe which 65 connects with the gas-supply-pipe and comprising a gas passage connected at its lower end with the chamber below the partition in the pipe which is secured to the gas-supply-pipe; a valve in said passage; and a tube 70 closed at its upper end, connected at its lower end with said passage and extending up through the lower wall of the burner and with its upper portion near and substantially parallel with the expansion-tube, said upper portion being provided with perforations in the side next the expansion-tube, for the 75 purpose set forth.

In testimony whereof I have signed my name to this specification in the presence of 80 two subscribing witnesses.

GEORGE H. JENNINGS.
